SNAP SWITCH AND CONTACTS THEREFOR

James J. Cooper, St. Louis, Mo., assignor to
H. Raymond Koch, St. Louis, Mo.

Application April 23, 1948, Serial No. 22,918

5 Claims. (CL. 200—166)

1

This invention relates to snap switches, and more particularly to toggle snap switches such as are used on switch panels, walls and the like.

Among the several objects of the invention may be noted the provision of a snap switch of the toggle type embodying an improved simplified mode of mounting the parts therein including the contacts; the provision of switch structure of the class described providing for ready assembly of the contacts with the body of the switch; the provision of improved simplified one-piece contact members for such switches; and the provision of a switch such as described which is compact, economical to manufacture and reliable in operation. Other objects will be in part apparent and in part pointed out hereinafter.

The invention accordingly comprises the elements and combinations of elements, features of construction, and arrangements of parts which will be exemplified in the structures hereinafter described, and the scope of the application of which will be indicated in the following claims.

In the accompanying drawing, in which one of various possible embodiments of the invention is illustrated,

Fig. 1 is a plan view of a snap switch embodying the invention;

Fig. 2 is an enlarged central longitudinal section through the snap switch of Fig. 1, parts being broken away;

Fig. 3 is an enlarged transverse section;

Fig. 4 is a plan view of Fig. 2 with certain parts removed to show the interior of a receptacle of the switch;

Fig. 5 is a side elevation of the switch on a reduced scale;

Fig. 6 is a detail of a blank from which a contact member for the switch is made;

Fig. 7 is a side elevation of the completed contact member;

Fig. 8 is an end elevation of Fig. 7 as viewed from the right;

Fig. 9 is a perspective view of the contact member; and,

Fig. 10 is a perspective view of an insulating member.

Similar reference characters indicate corresponding parts throughout the several views of the drawings.

Referring to the drawing, the snap switch of this invention is shown to comprise a support consisting of a receptacle or casing 1 formed of insulating material and having a bottom wall 3, parallel side walls 5 and end walls 7, forming a generally rectangular recess 9. The receptacle is preferably molded in one piece of a suitable

2

insulating plastic material. The side walls 5 are molded interiorly with ribs 11 at their approximate centers. These ribs extend from the bottom wall, with which they are integral, to the upper edge of the side walls. At their upper ends, the ribs are stepped as indicated at 13. The ribs are formed with generally V-shaped bearing notches 15 extending downward from their steps 13 and with arcuate bearing notches 17 in their reduced upper ends. The two ribs on the opposed side walls and the bearing notches therein are transversely aligned. Each side wall is also formed with an open-ended slot 19 leading downward from its upper edge to the bottom wall 3 and located immediately adjacent one of the end walls 7. The two slots in the opposed side walls are transversely aligned. The side walls are formed with opposed keys 21 on the opposite sides of the slots.

Each end wall 7 is recessed in its outer surface as indicated at 23 to provide an outwardly extending flange 25 at its upper end. Receptacle 1 is molded interiorly with narrow ribs 27 at the approximate centers at the end walls. These ribs extend upward from the bottom wall 3, with which they are integral, and are formed with inclined steps 29 at their upper ends. The bottom wall 3 has an arcuate upper surface 30 between the end ribs 27 curved on a radius from a center in the bearing notches 15. To strengthen the bottom wall 3 where its cross section is reduced by the provision of the arcuate surface and where the reinforcing effect of side walls 5 is absent at the slots 19, the receptacle is molded with an arcuate rib 31 on the arcuate surface 30 extending from one end rib 27 to the other and integral at its ends with the end ribs.

A generally U-shaped switch blade 33 is pivotally suspended in the bearing notches 15 for swinging movement into and out of bridging engagement with respect to a pair of contact members, generally designated 35, mounted in the slots 19 on opposite sides of the recess 9 at one end thereof. As illustrated, blade 33 comprises a generally U-shaped conducting sheet metal member, of brass or the like, having outwardly extending trunnions 35 at the upper ends of its vertical arms for bearing engagement in notches 15. The transverse bar of the U-shaped switch blade is formed with an upwardly extending projection 37 and has a recess 39 to clear the arcuate rib 31 on the arcuate surface 30 of the receptacle. The blade is adapted to swing between limiting positions determined by engagement of its lower end with the end ribs 27.

An operating lever 41 of insulating material

has trunnions 43 extending transversely from opposite sides thereof by means of which it is pivoted for rocking movement in the arcuate bearing notches 17. The lever is preferably molded of any suitable plastic material and is provided with a projection 45 at its lower end. A coil spring 47 is compressed between the lower end of the lever and the transverse bar of the U-shaped switch plate 33. Projections 37 and 45 enter the ends of the spring to retain it into position. The lever 41, spring 47 and blade 33 are retained in position by a mounting strap 49 secured to the receptacle 1 by screws 51 extending through the end flanges 25 of the receptacle. This strap has a central opening 53 through which the lever extends out of the receptacle. On opposite sides of opening 53, the strap has arcuate raised portions 55 engaging over trunnions 43. Lever 41 has shoulders or wings 57 adapted for engagement with the steps 29, the latter serving as stops to limit rocking movement of the lever. Shoulders 57 are provided on their outer surfaces with the usual "On" and "Off" indicia.

The above-described arrangement is such that with lever 41 in its "On" position shown in Fig. 2, with the shoulder 57 of the lever toward the contact end of the receptacle in engagement with the step 29 of the end rib 27 at the left-hand end of the casing, the switch blade 33 is in its limiting position determined by its engagement with the left-hand end rib 27 and engages the contact members 35 on opposite sides of the recess 9 in the receptacle to complete a circuit therebetween. When the lever is rocked clockwise from that position, as viewed in Fig. 2, spring 47 rocks counterclockwise about the lower end of the switch blade 33 until it overcenters, whereupon it snaps the switch blade away from the contact members. The switch blade rocks counterclockwise in its bearing notches 15 until it strikes the other end rib 27. The lever 41 rocks clockwise to its "Off" position wherein its right-hand shoulder 57 engages the step 29 of the right-hand end rib 27. When the lever is rocked counterclockwise as viewed in Fig. 2 from its "Off" position, spring 47 drives the switch blade back into circuit-closing position between the contact members 35.

The two contact members 35 are identical in construction. Each is formed from the flat sheet metal blank B, of brass or the like, illustrated in Fig. 6. This blank is shaped to have a generally rectangular terminal portion 61 and a contact clip portion 63 joined to the terminal portion by a narrow neck 65 extending centrally from the edge 67 of the terminal portion. The blank is slit as indicated at 69 and 71. Slits 69 extend inward from the edge 67 at the sides of neck 65, thereby forming two ears 73 on opposite sides of the neck. Slits 71 extend inward from the opposite edge 75 of the terminal portion, thereby forming two ears 77 at the two respective corners of the terminal portion, and an ear 79 intermediate the ear 77.

The blank is bent at the neck into generally V-shape, as illustrated in Figs. 7-9. The ears 73 are bent out of the plane of the terminal portion 61 in the direction opposite to the bend of the neck. This provides a keyway at the edge margin 67 of the blank. The ears 77 are bent in one direction out of the plane of the terminal portion and the ear 79 is bent in the opposite direction out of the plane of the terminal portion. This provides a keyway at the edge mar-

gin 75 of the blank parallel and opposite to the keyway in the margin 67. A central aperture 81 in the terminal portion 61 of each contact member is tapped to receive a terminal screw 83 for connecting wires to the contact members. The screws 83 extend substantially perpendicular to the side walls 5 of the receptacle 1 when the contact members 35 are assembled with the receptacle, and are threaded into the terminal portions from the outside of the receptacle.

The contact members 35 have their terminal portions 61 keyed in the respective slots 19 substantially coplanar with the respective side walls 5 by engagement of the keys 21 in the keyways 15 in the margins of the terminal portions, and have their reflexed resilient contact clip portions 63 extending within the recess 9 toward the end wall 7 adjacent the slots 19 (Fig. 4). Ears 13 and 17 lie on the outside of the keys 21, and the ears 79 and neck 65 lie on the inside of the keys. The contact members are assembled with the receptacle simply by sliding them downward in the slots 19, with the keys 21 entered between their respective ears, until the lower edges of the contact members engage the lower edges of the slots. This positions the contact clip portions 63 of the contact members in opposed convergent relation so that they are adapted to be bridged and spread apart by the lower end of the switch blade 33 as it swings between them. The curved portions of the contact members at their necks 65 facilitate the entrance of the lower end of the switch blade 33 between the contact clip portions 63.

The contact members 35 are held in position within the lower ends of the slots by means of insulating retainers 85 (Fig. 10). Each of these consists of a rectangular piece of fibre or the like having ears 87 at the corners thereof struck out from the plane of the retainer in one direction, and ears 89 intermediate the corner ears struck out in the opposite direction to form keyways at two opposite margins of the retainers. The retainers 85 are held in the slots over the contact members by engagement of keys 21 in their keyways. They are assembled with the receptacle 1 simply by sliding them downward in the slots 19 after contact members 35 have been mounted in position, with the keys 21 entered between the ears 87 and 89. Mounting strap 49 extends over the slots 19 to hold the retainers 85 and contact members 35 in place in the slots.

The mounting strap 49 extends beyond the ends of the receptacle for mounting the latter in a recess in a wall in the usual manner. The strap, as illustrated in Fig. 1, is formed with winged portions 91 at its ends for cooperation with a first type of wall mounting. The strap is scored as indicated at 93 so that these winged portions may be readily broken off if not required and the switch mounted by means of screws extending through elongate apertures 95 in the strap inward of the score lines 93. Apertures 95 are in portions 97 of the ends of the strap adapted to be broken off at score lines 99 if a shorter strap is required for mounting purposes. The strap is provided with apertures 101 within the score lines 99 for mounting purposes when the portions outward of score lines 99 are broken off.

From the above, it will be clear that assembly of the contact members 35 with the receptacle 1 in the process of manufacturing switches of this invention is quite simple. The process is simplified further due to the fact that the right and left hand contact members on opposite sides of

the recess 9 are of identical construction despite the fact that they are mounted in opposed relation. Thus, the assembly of the switch does not involve any necessity for selecting a particular contact for a particular side of the receptacle. Also all parts such as shown in Figs. 9 and 10 may be selected from a common supply of each, since each may be used indiscriminately either on the right or left of the switch.

In view of the above, it will be seen that the several objects of the invention are achieved and other advantageous results attained.

As many changes could be made in the above constructions without departing from the scope of the invention, it is intended that all matter contained in the above description or shown in the accompanying drawing shall be interpreted as illustrative and not in a limiting sense.

I claim:

1. In a switch, an insulating support having two side walls, each wall having a slot therein leading inward from an edge thereof with the two slots transversely aligned, each wall being provided with opposed keys extending into its slot from opposite sides of the slot, a pair of contact members each mounted in a respective slot, each contact member comprising a one-piece sheet metal member having a generally rectangular terminal portion substantially coplanar with the respective side wall and joined to a contact clip portion by a narrow neck extending substantially centrally from a side margin of the terminal portion, the contact member being bent at the neck so that its terminal and clip portions are in the general shape of a V, ears at said side margin of the terminal portion on opposite sides of the neck struck out from the plane of the terminal portion in the direction opposite to the bend of the neck to define with said neck a keyway, ears at the opposite side margin of the terminal portion struck out in opposite directions from the plane of the terminal portion to define another keyway, the terminal portions of the two contact members being keyed in the respective slots by engagement of the keys in their keyways with the contact clip portions extending into the space between said walls in opposed convergent relation for resilient engagement with a switch blade movable between said clip portions to spread them apart.

2. A snap switch comprising an insulation receptacle having a bottom wall, end walls and parallel side walls, each side wall having a slot leading from its upper edge toward the bottom wall adjacent one end wall, a pair of contact members each mounted in a respective slot, each contact member comprising a terminal portion substantially coplanar with the respective side wall and slidably keyed to the respective side wall at the sides of the slot therein, and a resilient contact clip portion extending into the receptacle from the keyed margin of the terminal portion remote from said one end wall, the contact clip portions of the two contact members being opposed to one another and converging toward said one end wall, terminal screws threaded into said terminal portions substantially perpendicular to the side walls from the outside of the receptacle, a switch blade pivoted in the receptacle for swinging movement into and out of closed-circuit posi-

tion wherein it engages and spreads said contact clip portions apart, and a toggle linkage including an operating lever extending out of the receptacle for operating said blade with snap action.

3. A snap switch comprising an insulation receptacle having a bottom wall, end walls and parallel side walls, each side wall having a slot therein leading from its upper edge toward the bottom wall adjacent one of the end walls and provided with keys on the opposite sides of the slot, a pair of contact members each mounted in a respective slot, each contact member comprising a terminal portion substantially coplanar with the respective side wall and having keyways at two opposite side margins thereof keyed in its slot by engagement of said keys in said keyways, and a resilient contact clip portion extending into the receptacle from one of the keyed side margins of the terminal portion, the contact clip portions being opposed to one another and convergent, terminal screws threaded into said terminal portions substantially perpendicular to the side walls from the outside of the receptacle, a switch blade pivoted in the receptacle for swinging movement into and out of closed-circuit position wherein it engages and spreads said contact clip portions apart, and a toggle linkage including an operating lever extending out of the receptacle for operating said blade with snap action.

4. A snap switch as set forth in claim 3 wherein the contact members are mounted in the lower ends of the slots, and further including a pair of insulation retainers each mounted in a respective slot to hold the contact members therein, each retainer having keyways in two opposite margins thereof keyed in the upper end of its slot by engagement of the keys in its keyways, and a mounting strap fixed to the top of the receptacle holding said retainers and contact members in the slots.

5. A contact member for use in snap switches and the like comprising a sheet metal blank having a generally rectangular terminal portion joined to a contact clip portion by a narrow neck extending substantially centrally from one margin of the terminal portion, said blank being bent at the neck into generally V shape, said terminal portion having ears at said one margin on opposite sides of the neck struck out from the plane of the terminal portion in the direction opposite to the bend of the neck to form with said neck a keyway, said terminal portion also having ears at its opposite margin struck out from the plane of the terminal portion in opposite directions forming a keyway at said opposite margin parallel and opposite to said first-named keyway.
